UNITED STATES PATENT OFFICE.

CARL A. MONSON AND HARRY GEARING, OF LOS ANGELES, CALIFORNIA, ASSIGNEES,
BY MESNE ASSIGNMENTS, TO HADLEY TAG & MACHINE CO., OF LOS ANGELES, CALI-
FORNIA, A CORPORATION OF CALIFORNIA.

DISCHARGE MECHANISM.

Original application filed February 14, 1920, Serial No. 358,746. Divided and this application filed
August 28, 1922. Serial No. 584,903.

This invention relates to discharge mechanism such as disclosed in our application for tag making and printing machines, filed Feb. 14, 1920, Serial No. 358,746, from 5 which application the subject-matter hereof has been divided out.

The main object of our invention is to provide a discharge mechanism by means of which identification, shipping and similar 10 tags may be discharged from tag making machines in piles or stacks ready for storage or packing and shipment or other disposition.

The invention has for further objects the 15 provision of a machine of the character stated which will be relatively simple and inexpensive in construction when these factors are taken into consideration with positiveness in operation, capability of long 20 continued operation without need of repair or replacement, durability, and general efficiency and serviceability.

The invention consists in the novel and useful provision, construction, combination, 25 relative arrangement, inter-relation and association of parts, members, features and elements, as well as the mode of operation of the same, all as developed in the specification and depicted in the drawing.

30 In the drawing:

Figure 1 is a vertical longitudinal section of our discharge mechanism;

Figure 2 is a detail sectional view taken 35 on the line x^2-x^2 of Fig. 1; and,

Figure 3 is a view of a unit of four tags which may be discharged from a tag making machine by our discharge mechanism.

Corresponding parts in all the figures 40 are designated by the same reference characters.

Referring particularly to the drawing, which shows one form of the mechanism constituting the invention, from which many departures may be made in variation 45 of construction, in adapting the machine to varying conditions in kinds and use of service, A designates the main frame which supports the leading elements and members of the mechanism; R designates means for severing the tag units or groups of units, such as shown in Fig. 3, after their impression; S means for receiving and accumulating such severed tags or groups of tags or

tag units, and T a stacker to which such units or tag units are delivered intermittently from the accumulator S, and to which stacker such tag or tag units are fed in groups reversed end for end to ensure an even stacking thereof. V designates a main drive shaft from which power is taken for 55 the operation of the several members and features of the machine in any suitable manner.

The printed and eyeletted tag stock b may be fed by a pair of rolls Q from the tag 60 making machine to the severing means R of our discharge mechanism, for severing said stock into tags or tag groups. These means R comprise a cylinder 53 which is provided with a plurality of transverse 65 knives 54, certain of which may be of a limited length so as to but partially sever the stock between the tags of a given group, as shown in Figure 3, while the remaining knife may be of full width to entirely sever 70 the organized stock and cut from it the group of four or other number of tags shown in Figure 3. Such knives cooperate with a stationary knife or cutter bar 55, the cylinder 53 being disposed above the stock and the bar or knife 55 being disposed beneath it. The severed tags or tag group, now complete, may be delivered from the machine 75 at this point, or may be passed to the accumulator comprising an endless belt or conveyor 56, trained about suitable rolls 57, one of which is a driving roll fast upon a transverse shaft 58, to which is applied a loose 80 clutch member 59 carrying a gear 86, said clutch member cooperating with a splined 85 clutch member 60 operating lengthwise of the shaft 58 intermittently, by a rocker arm 61, one limb of which is actuated by a cam 62 upon a drive shaft 63 operated through a train of gears 64, 65, 66 and 67, thus taking power from the main drive shaft V 90 through gear 82 and bevel gears 83 and 84, the bevel gear 83 and the gear 82 being secured on the stud shaft 85 which is journaled in the frame A, and the bevel gear 100 84 being secured on shaft V. The clutch member 59 receives its drive through a train of gears 68, 69, 70 and 86, which train of gears is driven through mitre gears 71 and 81 from the main drive shaft V, the mitre gear 81 and the gear 69 being secured on

105

the stud shaft 88 which is journaled in the frame A, and the mitre gear 71 being secured on the shaft V. Thus the accumulator endless belt 56 is given an intermittent movement, serving to discharge from it each stack of the predetermined number of tags or tag groups which are temporarily kept in place by a tension roller 72, such discharge taking place on to the stacker member T. This member consists of an inclined rotatable table 73, upon which the stacked tags or tag groups are retained by the cooperation of an inclined wall 74. After each period of advancement of the accumulator belt 56 the standard or central support shaft 75 of the rotatable table 73 is given a half rotation in a bar 76 threaded to receive a threaded portion 76^a of the shaft 75 and which half rotation is produced by a gear 77 loose from the shaft 75 and adapted to cooperate with a splined clutch member 78 normally retained out of engagement with the clutch gear 77 by a cam 79 at one end of the shaft 63 above mentioned. The clutch gear 77 is rotated by a worm gear 80 secured on shaft 88 and is driven by meshing mitre gears 71 and 81, the mitre gear 71 being on the shaft V.

It is not believed that any separate definition of the mode of operation of the machine will be required in order to make clear the performance and action of the mechanism inasmuch as there has been heretofore defined the performance of each member or feature of the machine, and the sequence in which these performances take place.

Having thus disclosed our invention, we

claim and desire to secure by Letters Patent:

1. In a machine of the character disclosed, 40 means for stacking completed tag units, a transferring accumulator comprising a continuous belt member for conveying the tag units to the stacking means, means being provided for intermittently operating said 45 transferring accumulator, and means for temporarily maintaining a pre-determined number of tag units on said transferring accumulator; said means for stacking completed tag units including an inclined rotatable table, and an inclined wall member 50 acting in conjunction with the table.

2. In a machine of the character disclosed, means for stacking completed tag units, a transferring accumulator comprising a continuous belt member for conveying the tag units to the stacking means, means being provided for intermittently operating said transferring accumulator, and means for temporarily maintaining a pre-determined number of tag units on said transferring accumulator; said means for stacking completed tag units including an inclined rotatable table, and an inclined wall member 55 acting in conjunction with the table; 60 there being means for intermittently rotating said table after each period of intermittent movement of the transferring accumulator.

In testimony whereof, we have signed our 70 names to this specification.

CARL A. MONSON.
HARRY GEARING.
